CLAIM

The ornamental design for a display or portion thereof with graphical user interface, as shown and described.

DESCRIPTION

1 Claim, 1 Drawing Sheet
